CHRISTMAS TREE HOLDER

Karl Johan Hansson, Satrabrunn, Sweden, assignor to Nils Berggren, Herman Fernstrom, and Gustav Ostlund, all of Vasteras, Sweden, and Simon Jansson, Malung, Sweden

Application March 22, 1947, Serial No. 736,550
In Sweden December 31, 1945

Section 1, Public Law 690, August 8, 1946
Patent expires December 31, 1965

5 Claims. (Cl. 248—44)

1

The present invention relates to a Christmas tree holder comprising a receptacle, preferably of a conical shape, and a frame having rods made, for instance, of spring steel. The upper free ends of the rods enter openings provided in the receptacle, which is displaceable in a vertical direction relative to the frame so as to force said free ends inwardly toward the center of the receptacle upon a downward movement of the latter. When the receptacle is displaced downwardly, the rods permit a quick and safe locking of the tree placed in the receptacle. The object of the invention is to improve a Christmas tree holder of said type by permitting the Christmas tree not only to be rapidly secured but also to be adjusted in its vertical position at the same time.

Further objects and advantages of the invention will be apparent from the following description considered in connection with the accompanying drawing, which forms a part of this specification, and of which:

The figure is a part sectional view of a Christmas tree holder in accordance with the invention.

A water receptacle *a*, into which the trunk of the tree is adapted to be thrust, is of a rounded configuration tapering downwardly. The bottom of the receptacle consists of the head of a screw *b*. The receptacle rests on four supports *d* of round iron or band steel, said supports being secured to a horizontal ring *e* underneath the receptacle. The upper free end portions of the supports are thrust through apertures in the upper rim *f* of the receptacle, which rim is reinforced by a flange, said end portions becoming resilient to a certain extent by suitably adapting the thickness of the material of the supports. An increased stability of the supports may be obtained by means of a ring *g* keeping the supports together at the bottom, and the plates *h* secured to the flange of the receptacle and folded down on both sides of the supports counteract any tendency toward a twisting movement on the receptacle.

A lock-nut *i* having a hand wheel *j* is provided at the bottom with a flange *k* bearing from below against a clamping washer *l*, and is threaded on the inside thereof, so as to permit of being screwed up on the screw *b* to lock the tree. As will be observed from the drawing the washer *l* is dished to spherical form about a center on the axis of the receptacle located approximately at the upper end of the receptacle at the plane of the connection between the receptacle and the supports *d*.

2

The tree is mounted in the following manner. The lower end of the trunk is placed in the receptacle *a*, which is loaded by the weight of the tree so as to sag downwardly owing to its resilient suspension in the supports *d*, the upper portions of said supports being thus pressed inwardly against the trunk of the tree. The maximum of these movements of the receptacle and the supports without a tree is shown by dash lines in the drawing. Now the tree can be straightened into a vertical position, inasmuch as the receptacle with its lock-nut, hand wheel and clamping washer is swingable at the bottom in all directions toward the inner edge of the ring *e*. After the tree has been straightened by a manipulation of the hand wheel, the friction between the clamping washer *l* and the ring *e* at the bottom and between the flange *f* of the receptacle and the supports *d* at the top is entirely sufficient to keep the tree in the given position.

The supports, three or more in number, may be provided at the upper ends thereof with special gripping members *m* for the trunk. They may also be shorter or pivotally arranged and made dependent on some other spring system. Furthermore, the supports may converge above the receptacle, the same being then guided by fixed or movable holders.

Locking may also be effected by means of an eccentric, a lever, by rollers, or pawls, or by means of a chain or a spring.

The receptacle may be provided internally at the bottom with a holder for the trunk. The receptacle may also be carried by members other than said supports. The lock-nut *i* and the hand-wheel *j* may be placed underneath the clamping washer *l*. In certain cases, the ring *g* may be omitted. Otherwise, materials comprising pipes or flat bar iron or steel may be used for the Christmas tree holder, which latter may also be made collapsible or adapted to be taken to be pieces to facilitate packing and transport. Obviously, the Christmas tree holder may also be used for other purposes where similar conditions manifest themselves.

While one more or less specific embodiment of the invention has been shown, it is to be understood that this is for purpose of illustration only, and the invention is not to be limited thereby, but its scope is to be determined by the appended claims.

What I claim is:

1. A support for an elongated object comprising a base, yieldably mounted arms extending upwardly and inwardly from said base and ter-

minating outwardly of the vertical center line thereof, a receptacle having apertures in the side walls adjacent the upper end thereof slidably receiving the inner extremities of said arms, a member depending from the bottom of said receptacle and extending through an opening in said base, said opening being substantially larger than said member, and clamping means carried by said member for engagement with the lower surface of said base whereby upon movement of said receptacle and arms downwardly under the weight of an object disposed therein said inner extremities will move inwardly into engagement with said object, said member being movable laterally in any direction in said opening to adjust the vertical alignment of said object and whereby upon movement of said clamping means into engagement with said base said object will be clamped in adjusted position.

2. A support for an elongated object comprising a base, yieldable arms extending upwardly and inwardly from said base and terminating outwardly of the vertical center line thereof, a receptacle having apertures in the side walls adjacent the upper end thereof slidably receiving the inner extremities of said arms, a member depending from the bottom of said receptacle and extending through an opening in said base, said opening being substantially larger than said member, and clamping means including a dished element carried by said member having a concave upper surface for engagement with the lower surface of said base, said member being swingable laterally in any direction in said opening about the upper end portion of said receptacle as a center to adjust the vertical alignment of said object, whereby upon movement of said receptacle and arms downwardly under the weight of an object disposed in said receptacle, said inner extremities will move inwardly into engagement with said object and upon movement of said clamping means to bring said dished element into engagement with said base, said receptacle will be clamped in laterally adjusted position by force exerted axially of the receptacle regardless of the lateral position of the clamping means relative to said base.

3. A support for an elongated object comprising a base, yieldable arms extending upwardly and inwardly from said base and terminating outwardly of the vertical center line thereof, a flared receptacle having apertures in the side walls adjacent the upper end thereof slidably receiving the inner extremities of said arms, a member depending from the bottom of said receptacle and extending through an opening in said base, said opening being substantially larger than said member, and clamping means carried by said member for engagement with the lower surface of said base whereby upon movement of said receptacle and arms downwardly under the weight of an object disposed therein said inner extremities will move inwardly into engagement with said object, said member being movable laterally in any direction in said opening to adjust the vertical alignment of said object and whereby upon movement of said clamping means into engagement with said base said object will be clamped in adjusted position.

4. A support for an elongated object comprising a base, yieldable arms extending upwardly and inwardly from said base and terminating outwardly of the vertical center line thereof, a flared receptacle having apertures in the side walls adjacent the upper end thereof slidably receiving the inner extremities of said arms, a screw threaded member depending from the bottom of said receptacle and extending through an opening in said base, said opening being substantially larger than the diameter of said member, a nut received on said member and having finger engaging means and a dished washer having a substantially spherical concave upper surface carried by said nut for engagement with the lower surface of said base whereby upon movement of said receptacle and arms downwardly under the weight of an object disposed therein said inner extremities will move inwardly into engagement with said object, said member being swingable laterally in any direction in said opening about the upper end portion of said receptacle as a center to adjust the vertical alignment of said object and whereby upon rotation of said nut to move said washer into engagement with said base said object will be clamped in adjusted position.
5. A support for an elongated object comprising a base, yieldable arms extending upwardly and inwardly from said base and terminating outwardly of the vertical center line thereof, a cone shaped receptacle having circumferentially spaced apertures adjacent the upper end thereof slidably receiving the inner extremities of said arms, a screw threaded member depending from the bottom of said receptacle and extending through an opening in said base, said opening being substantially larger than the diameter of said member, a nut received on said member and having finger engaging means and a spherically curved washer carried by said nut having a concave upper surface for engagement with the lower surface of said base, whereby upon movement of said receptacle and arms downwardly under the weight of an object disposed therein, said inner extremities will move inwardly into engagement with said object, said member being swingable laterally in any direction in said opening to adjust the vertical alignment of said object and whereby upon rotation of said nut to move said washer into engagement with said base said object will be clamped in adjusted position.
